UNITED STATES PATENT OFFICE.

JOHN PFEIFER, OF SPRINGFIELD, OHIO, ASSIGNOR TO THE SPRINGFIELD AUTO LOCK COMPANY, OF SPRINGFIELD, OHIO, A CORPORATION OF OHIO.

PERMUTATION LOCKING MECHANISM FOR GEAR-SHIFTING LEVERS.

Application filed December 5, 1921. Serial No. 520,099.

To all whom it may concern:

Be it known that I, JOHN PFEIFER, a citizen of the United States, residing at Springfield, in the county of Clark and State of Ohio, have invented certain new and useful Improvements in Permutation Locking Mechanism for Gear-Shifting Levers, of which the following is a specification.

My invention relates to a permutation lock especially designed for the gear shifting levers of automobiles.

One of the objects of my invention is to devise a mechanism of the character referred to which can be installed without altering the shifting lever or other parts associated therewith.

Another object of my invention is to provide a locking mechanism which will not only lock the lever against shifting movement, but also prevent the removal of the lever.

A further object of my invention is to devise a mechanism of this character which will be simple in construction, economical in manufacture and effective in operation.

In the accompanying drawings:—

Fig. 1 is a front elevation partly in section showing a gear shifting lever and its housing of conventional form, with my improved locking devices applied thereto.

Fig. 2 is a side elevation of the same.

Fig. 3 is a top plan view of the same.

Fig. 4 is a plan view of the clamping ring.

Referring to the drawings, 1 represents a portion of the supporting housing for the shifting lever 2, the shifting lever being pivotally connected to the rod or shaft 3 journaled in the walls of the housing so that the lever may be shifted laterally from neutral position and then forwardly or rearwardly in the usual way. The housing has the usual removable outer casing 4 and the upper end of the housing and casing are of semi-spherical form to receive the usual semi-spherical cap 5, the neck 5^a of which surrounds the lever. The lever and housing shown are simply illustrative of one example of a selective type of shifting devices, my improvement being applicable to practically all the different constructions of this type without alteration therein.

In installing my devices, I employ a two-part ring, the members of which are indicated by the reference characters 6 and 7.

The members of this ring are enlarged at their points of juncture so as to receive clamping screws 8 by which the ring may be clamped firmly about the casing 4 near the lower end thereof, and to further insure the ring being held in position about the casing. I also employ screws 9 which are threaded in the ring members 6 and also threaded through the casing 4 and into the housing 1. One of these ring members, in the present case the member 7, is provided with a pair of upstanding ears 10 to which are pivotally connected by pins 11 the arms 12 of a supporting frame 13 which has projections 14, 15 and 16 positioned to form a channel to embrace the shifting lever 2 when the frame is aligned with the lever. Also projecting from the frame 13 is a pair of angularly arranged brackets 17 and 18 which have aligned apertures to receive a locking bolt 19 and between which and about the bolt are a series of rotatable sleeves 20 which form the permutation locking mechanism. Inasmuch as the details of this permutation locking mechanism are described in my Letters Patent No. 1,363,432, dated Dec. 28, 1920, it will not be necessary to explain this mechanism any more than to say that when the locking bolt 19 is in the position shown in full lines, the frame 13 may be swung to or from locking position and that, when the frame 13 has been swung to locking position and the bolt projected to the dotted line position, the frame 13 is locked to the lever, the rings or sleeves 20 being rotated to lock the bolt in the manner fully described in the patent referred to.

The frame 13 in its normal position lies on the floor board between the shifting lever and the dash of the vehicle, the frame being swung rearwardly to align it with the lever for locking purpose, bringing the projections 14, 15 and 16 in the path of the lateral movement of the lever so that when the frame 13 has been locked to the lever, with the lever in neutral position, the projections will prevent any lateral movement of the lever from neutral position. It will also be noticed that the frame 13 is so formed as to closely fit the cap 5 thereby preventing its removal and also the removal of the casing 4, which thus prevents the shifting lever from being detached from its connections and thereby released from the locking devices.

In order to prevent access to the clamping screws 8 and the holding screws 9, I form the arms 12 of the supporting frame with projections 21, which projections, when the frame is in its locking position, conceal these screws so that removal thereof is impossible. It will be noticed that the pivot pins 11 have their ends swaged so that their removal is guarded against.

10 By the construction described it will be seen that a combination lock for the gear shifting lever of an automobile is provided which can be readily installed upon the conventional form of lever without the necessity of altering the lever, or substituting a new lever of special construction, or with any alteration in any of the other parts.

Having thus described my invention, I claim:—

20 1. In a device of the character described, the combination, with a gear shifting lever, of a movable support having embracing parts for said lever when aligned therewith, and mechanism carried entirely by said support for locking the same to said lever.

25 2. In a device of the character described, the combination, with a gear shifting lever, of a movable support having embracing parts for said lever to prevent shifting movement of said lever, and locking mechanism carried entirely by said support including a movable member arranged to cooperate with said support to lock the same to the lever.

30 3. In a device of the character described, the combination, with a gear shifting lever capable of lateral movement only when in neutral position, of a movable support arranged to be swung in alignment with said lever and having embracing parts for the same to prevent lateral movement of said lever, and locking mechanism carried by said support including a part cooperating with said support to lock the same to said lever.

35 4. In a device of the character described, the combination, with a gear shifting lever of conventional form, of a movable support having embracing parts for said lever and arranged to be moved in alignment therewith to prevent shifting of said lever, and permutation locking mechanism carried by said support including a slidable bolt to cooperate with said support to lock the same to said lever.

45 5. In a device of the character described, the combination, with a gear shifting lever of conventional form, of a pivoted support arranged to be swung in alignment with

said lever and having parts which embrace said lever, an angularly arranged slidable member on said support to cooperate with the same to lock the support to said lever, and permutation locking devices for said slidable member also carried by said support.

6. In a device of the character described, the combination, with a gear shifting lever of conventional form, of a pivoted support arranged to be swung in the direction of the forward and rearward movement of said lever, said support having embracing parts for said lever when aligned therewith to prevent lateral swinging of said lever, an angularly arranged movable member carried by said support and cooperating therewith to lock the support to said lever when aligned therewith, and locking devices carried by said support for said movable member.

7. In a device of the character described, the combination with a gear shifting lever and its housing, a cap for the upper end of said housing and movable thereover by the movement of said lever, of a pivotal frame arranged to swing in alignment with said lever and so formed as to embrace said lever and said cap to prevent shifting of the lever and removal of the cap, and means carried on said frame for locking the same to the lever.

8. In a device of the character described, the combination, with a gear shifting lever and its housing, of a removable support secured to said housing, a frame pivoted to said support and arranged to swing in alignment with said lever, said frame having embracing parts for said lever to prevent shifting of said lever, means carried on said frame for locking the same to said lever, and means associated with said frame arranged to prevent removal of said support.

9. In a device of the character described, the combination, with a gear shifting lever and its housing, of a support including screws for securing the same to said housing, a frame pivotally connected with said support and arranged to be swung in alignment with said lever, said frame having parts thereon to embrace said lever, means for locking said frame to said lever, and parts on said frame arranged to conceal said screws when said frame is in its locking position.

In testimony whereof, I have hereunto set my hand this 17th day of November, 1921.

JOHN PFEIFER.
